[57] CLAIM

The ornamental design for a limb and/or body restraint,
as shown and described.

DESCRIPTION

FIG. 1 is a perspective view of a limb and/or body restraint showing my new design, with portions broken away to indicate an indeterminate length;

FIG. 2 is a perspective view as seen from the opposite side of FIG. 1; and

FIG. 3 is a bottom plan view thereof.

FIG. 1

FIG. 2

FIG. 3
